UNITED STATES PATENT OFFICE.

ALFRED CHRISTOPHE KOERNER, OF PARIS, FRANCE, ASSIGNOR TO THE HOTCHKISS ORDNANCE COMPANY, (LIMITED,) OF LONDON, ENGLAND.

EXPLOSIVE PROJECTILE.

SPECIFICATION forming part of Letters Patent No. 374,874, dated December 13, 1887.

Application filed September 7, 1887. Serial No. 249,000. (No model.)

To all whom it may concern:

Be it known that I, ALFRED CHRISTOPHE KOERNER, a subject of the Queen of England, residing at Paris, in the Republic of France, 5 have invented certain new and useful Improvements in Explosive Projectiles, fully described and represented in the following specification, and the accompanying drawings, forming a part of the same.

10 This invention relates to the construction of explosive projectiles for ordnance, it being the object of the invention to insure the maximum regularity of systematic fragmentation by the explosion of the bursting charge. This 15 object is attained by certain peculiarities of construction, which will be hereinafter fully described and pointed out.

The improvements constituting the invention are fully illustrated in the accompanying 20 drawings, in which—

Figure 1 is a longitudinal section, parts being shown in elevation, of an explosive projectile or shell constructed according to my invention. Fig. 2 is a cross-section taken on 25 the line 2 2 of Fig. 1. Fig. 3 is a plan view of one of the frangible missiles with which the shell is loaded. Fig. 4 is a cross-section of the same, showing also one of the loose balls; and Fig. 5 is a view similar to Fig. 1, illustrating 30 a modification, which will be hereinafter referred to.

Referring to said figures, it is to be understood that the body of the projectile consists of a tubular part, A, preferably made of steel, 35 and provided with internal longitudinal grooves a, to facilitate breakage upon the explosion of the internal charge. The front end of the tubular portion A is closed by a nose piece, 3, which is tapped for the fuse 4, 40 which is of the ordinary construction. The base of the tubular portion A is closed by a disk, 5, which is screwed or otherwise fastened in position. A band, 6, of soft brass or copper, encircles the projectile near its base and 45 serves to take the rifling of the gun to insure rotation.

As shown in Fig. 1, the bursting charge 9 of the projectile is located at the forward end

and communicates directly with the fuse, while the rear and main part of the interior of the projectile is filled with loose missiles, which, together with the fragments of the projectile itself, are to be scattered by the explosion. These missiles consist of star shaped pieces 7, of flangible metal and leaden or iron balls 8. The pieces 7 are formed with five or more arms or branches, according to the diameter of the projectile, and these branches are so formed, as best shown in Fig. 4, as to be greatly weakened at the points of their junction with the central part or body of the star, as shown at 10, so that they will readily be broken off by the shock occasioned by the explosion of the charge 9, thereby dividing the stars into practically uniform fragments. In placing the star-shaped pieces 7 in the projectile their arms are mismatched, as shown in Fig. 1, and thus cavities are formed, which serve to receive the balls 8. The arms of the pieces 7 are slightly countersunk, as shown, to afford seats for the balls. The pieces 7 and the balls, when thus assembled, form a practically solid column of sufficient strength to withstand the shock of the discharge of the gun and prevent the projectile from being deformed thereby.

The interstices between the pieces 7 and the balls 8 are preferably filled with powdered charcoal or other smoke-producing substance, in order to cause as much smoke as possible to facilitate observing the bursting of the projectile in the air.

The bursting charge 9, instead of being located in the front part of the projectile, may be located in the rear or base portion, as shown in Fig. 5. In this case communication between the charge and the fuse 4 is established through a central tube, 11, passing through openings in the pieces 7.

Having thus described the improvements constituting my invention, what I claim as new, and desire to secure by Letters Patent, is—

The herein-described explosive projectile, composed of the tubular portion A, having the internal longitudinal grooves, a, the nose-

iece 3, fuse 4, base-piece 5, band 6, of soft metal, star-shaped pieces 7, made of frangible metal, and having their arms weakened to facilitate breaking, balls 8, arranged between the arms of the star-shaped pieces 7, and the bursting charge 9, all substantially as described, and for the purposes set forth.

In testimony whereof I have hereunto set my hand in the presence of two subscribing witnesses.

ALFRED CHRISTOPHE KOERNER.
